No. 635,328.

Patented Oct. 24, 1899.

J. O. A. LAFOREST.
SERVICE BOX FOR SERVICE PIPES.

(Application filed June 2, 1898.)

(No Model.)

UNITED STATES PATENT OFFICE.

JOSEPH OCTAVE ALFRED LAFOREST, OF MONTREAL, CANADA.

SERVICE-BOX FOR SERVICE-PIPES.

SPECIFICATION forming part of Letters Patent No. 635,328, dated October 24, 1899.

Application filed June 2, 1899. Serial No. 719,123. (No model.)

To all whom it may concern:

Be it known that I, JOSEPH OCTAVE ALFRED LAFOREST, a subject of Her Majesty the Queen of Great Britain, residing at the city and district of Montreal, Canada, have invented certain new and useful Improvements in Service-Boxes for Service-Pipes; and I do hereby declare that the following is a full, clear, and exact description of the invention, such as will enable others skilled in the art to which it appertains to make and use the same.

This invention relates to an improvement in service-boxes for service-pipes, and has for its object to provide a box of this character so constructed as to permit of ready access to the cock of the service-pipe for operating the same.

A further object is to provide a service-box which is simple in construction, reliable in operation, of few parts, and which can be manufactured at a low cost.

To these ends the invention consists in a service-box constructed substantially as hereinafter illustrated and described, and defined in the appended claim.

Referring to the drawings, in which similar letters of reference indicate similar parts, Figure 1 is an elevation of the improved service-box constructed in accordance with this invention. Fig. 2 is a vertical central section of Fig. 1. Fig. 3 is a view in elevation of the operating-key in position on the rod which is broken off. Fig. 4 is a view in elevation of a detail partly broken. Fig. 5 is a perspective view of the base-plate, showing the operating-cock. Fig. 6 is a plan of the pipe-joint, showing the operating-cock.

In the drawings, A represents the base-plate of the improved service-box, which may be made of metal or other suitable material, preferably earthenware, vitrified clay, &c., and is of substantially rectangular form. Two opposite edges of the base-plate are offset at a and a', and an angular groove a² is formed along the entire length of these edges, as shown in Fig. 5. The upper surface of the base-plate is provided with a recess or socket a³, which extends across from side to side and is shaped to conform with the shape of the pipe-joint C and its operating-cock C', which is adapted to be received and held in said socket. Adjacent to the central portion of the socket a³ and on opposite sides thereof is

formed two semicircular grooves a⁴, which correspond substantially with the shape of said socket and are adapted to receive the lower edge of the cylindrical protecting-cone B, whereby the same is securely held to said base-plate. The cone B may be of any suitable material, preferably earthenware, vitrified clay, &c., and is substantially of the shape of a truncated cone having a height and diameter sufficient to cover and protect the cock and its operating-key. The lower edge of the cone B is provided with semicircular recesses b, arranged on opposite sides thereof to provide space for the ends of the pipe-joint C. The upper extremity of the cone B is provided with a suitable cap or collar b', of brass or other suitable non-corroding material, which is held thereon by the weight of the earth packed about it.

A tube D is movably sleeved in an opening of the cap b' and extends downwardly within the cone B to a point near the cock C' and may be formed of one or more jointed sections, according to the depth below the surface of the ground the base-plate is situated. A removable cover d is threaded to the upper end of the tube D, and, if desired, the contacting surfaces may be made of brass or other suitable non-corroding metal.

Within the tube D is arranged a rod E, the lower end of which is adapted to engage the head of the cock C' and is secured thereto in any suitable manner. The upper end of the rod E terminates some distance below the top of the tube D and is squared to receive the socket end of the operating-key F, whereby the rod may be turned and the cock opened or closed, as desired.

From the above description it is apparent that by means of this construction the pipe-joint is firmly supported in the base-plate and is fully protected from dirt, &c., and that while it is protected from being tampered with the cock can be readily reached and operated.

The offset edges of the base-plate insure the firm jointing together of two or more service-boxes where a series of them is necessary and serve to prevent transverse and vertical movement of the same with respect to each other.

While I have herein shown a preferred form of carrying my invention into effect, yet I do not desire to limit myself to such pre-

ferred details of construction, but claim the right to use any and all modifications thereof which will serve to carry into effect the objects to be attained by this invention in so far as such modifications and changes may fall within the spirit and scope of my said invention.

The construction and arrangement above described are such that should the tube D be vertically moved by the action of frost, &c., the position of the remaining parts is not disturbed, the said tube sliding freely through the opening in the collar b'.

The weight of the earth packed about the cone B keeps it firmly in place, while its shape prevents its displacement by the action of frost, &c.

I claim—

A service-box, comprising a base-plate provided with a recess to receive a pipe-joint and

semicircular grooves adjacent to said recess, a protecting-cone having its lower edge secured within said grooves and recessed at opposite sides to provide space for the ends of the said pipe-joint, a cap upon the top of said cone, a tube movably sleeved within an opening in said cap, the lower end of said tube extending to a point near the cock of said joint, a removable cap on the upper end of said tube, and an operating-rod arranged within said tube, having its lower end secured to said cap and its upper end squared to receive a key, substantially as described.

In witness whereof I have hereunto set my hand in the presence of two witnesses.

JOSEPH OCTAVE ALFRED LAFREST.

Witnesses:

WILLIAM B. ROBERTS,
A. W. YOUNG.
